GAS TREATMENT AND APPARATUS
THEREFORGeorge Franklin Russell, Jr., Baton Rouge, La.,
assignor to Aluminum Company of America,
Pittsburgh, Pa., a corporation of Pennsylvania

Application February 15, 1946, Serial No. 647,750

5 Claims. (Cl. 166—1)

1

This invention relates to improved methods for recovering from wells gaseous hydrocarbon fluids, particularly natural gas, and to improved systems for receiving, handling and treating such gases.

Among the problems encountered in the recovery of gaseous hydrocarbon fluids, such as natural gas, from the earth and placing the gas in usable form are the difficulties encountered in protecting from corrosion the recovery apparatus and particularly the casing elements of the well and the pipe or tube through which the gas is withdrawn from the well. Another problem encountered is the provision of efficient means by which the gas may be "dried," i. e., stripped of its moisture content. Since the corrosion difficulties just referred to are in large part caused by the moisture carried by the gas, these problems are, in a sense, related. Natural gas as it is recovered from the earth usually bears considerable moisture. As the gas moves upwardly from the relatively warm subterranean levels to the relatively cool levels, this moisture condenses upon the well casing and the gas carrying tube disposed therein and causes the corrosion herein referred to. When the natural gas also bears acidic components the corrosion effect may be considerably increased.

An important object of this invention is the provision of methods by which such corrosion may be minimized or substantially eliminated. Another object of the invention is to provide an efficient gas handling and treating system by which the first mentioned object may be realized. A further object of the invention is provision of an improved gas handling and drying system having new and novel features including an efficient combination of means for drying the gas by use of a sorbent and means for reactivating said sorbent. Yet another object is the provision of an efficient gas handling system in which the pressure of the recovered gas is utilized to effect certain operations in said system. These and further objects of the invention, as well as the advantages and benefits obtainable by the practice thereof, will more particularly appear from the following description. The drawing, which will be referred to in said description, illustrates in diagrammatic form a preferred system embodying the principles of this invention.

Referring to the drawing, the well illustrated therein consists of a conventional casing 10, which extends into the producing formation 11. Casing head 12 is likewise conventional and through it passes the tube 13 which collects the

2

gas and delivers the same to the gas handling and treating system. It is on the surfaces of the tube, the casing and the casing head that much of the corrosion difficulties occur. As the moisture-bearing gas passes from the earth to the relatively cool conditions existing above the surface of the earth, moisture condenses on the casing and particularly on the inner surface of tube 13. The resultant corrosion limits the useful life of tube 13 and, often, the life of casing 10. The method of this invention designed to minimize or eliminate these corrosion effects consists in mixing with the gas at the bottom of the casing and prior to its travel to the surface of the ground, of such amounts of a dry gas as are calculated to reduce the moisture content of the mixture thus formed below the point at which substantial condensation will occur in the gas carrying tube, i. e., below the dew point of the gas-dry gas mixture. The amount of dry gas necessary to this purpose will, of course, depend upon the original moisture content of the gas to be recovered and the temperature conditions prevailing during passage of that gas from the earth to the surface or to the next step of the gas handling operations, but is readily calculated when these conditions, which are easily ascertainable, are known. The nature of the dry gas is not important to this invention, in so far as concerns the reduction of the dew point of the gas being recovered. However, it is preferable to use as the dry gas a portion of the recovered gas which has been previously dried and, in any event, the dry gas should be substantially non-reactive with the materials from which the gas handling apparatus is formed and should preferably be a type which does not form explosive mixtures with the recovered gas. The manner in which the mixture between dry gas and the moisture-bearing gas is formed may vary with the choice of the operator, but conveniently the dry gas is merely forced under pressure downwardly to the bottom of the casing. For this purpose the dry gas may be furnished through the casing head by a pipe or tube, such as tube 14 shown in the drawing. The gas handling and treating apparatus which is particularly useful in the practice of the aforeslated method of this invention is shown in the drawing and will now be specifically described. The general purpose of the system is to prepare a natural gas for delivery to a consumer or to storage for later use. A specific purpose is to deliver to the well a quantity of dry gas for the purpose above stated. The general function of the system is to dry and

purify the gas, the principal drying means being a sorbent, such as adsorbent alumina, silica gel, or other known sorbent which is capable of being revived or reactivated. The adsorbent commercially available as "Activated Alumina" is particularly suitable. The preparation of such material is described in U. S. Patents 1,868,869 and 2,015,543. To these ends the specific system shown includes three identifiable but mutually interdependent circuits, viz., a receiving and treating circuit, a sorbent reactivating circuit, and a feed circuit designed to furnish dry gas under pressure to the well casing. Each of these circuits will now be described.

The receiving and treating circuit

The circuit is fed by gas issuing from the well through tube 13. The gas passes through heat exchanger 15, tube 16 and separator 17. From separator 17 the bulk of the gas moves through tube 18 and thence through one of the drying towers 19 or 20 for treatment with a sorbent. From the tower the gas flow continues through pipe 21, the bulk of the gas then passing through expansion motor 22, pipe 23, heat exchanger 15, and then through pipe 24 to the consumer or to storage. It will be noted that during the time the natural gas is being purified and dried, it is under substantially the pressure at which it entered the system, subject, of course, to changes in temperature and incidental losses. However, when the gas flow reaches expansion motor 22, the gas is expanded to cool it and the energy thus released is used to operate motor 22 to drive a compressor 34 for purposes later described. To this end the motor is any conventional device adapted to expand the gas and permit the expansion to operate a piston or like driving part. As the unpurified natural gas flows through heat exchanger 15, its temperature is reduced by the cooling action of the dried and purified gas which, having been expanded at expansion motor 22, passes through tube 23 to and through said heat exchanger. The unpurified and undried natural gas, now partially cooled by the action of the heat exchanger 15 just described, next is subjected to the action of separator 17. Here the condensate which may have resulted from the cooling action is collected and discharged through pipe 40 to a suitable place, while the gas passes to the drying tower. While, for convenience of illustration, only two drying towers are shown, it will be realized that any number of such towers may be used, the principle being that at any given time one or more of said towers are available for use, while one or more towers previously used are being reconditioned for future use. Thus, in the device shown, by manipulation of valves 41 and 42, one of the towers 19 and 20 may be placed in circuit with separator 17 and expansion motor 22, while the other tower is excluded from said circuit. For the purposes of drying, the tower contains a sorbent of the type above described.

The sorbent reactivating or reconditioning circuit

The purpose of this circuit is to divert from the receiving and treating circuit a portion of gas which is then heated to a proper temperature and passes through the inactive tower to recondition or reactivate the sorbent held therein. Thereafter this gas is returned to the receiving and treating circuit of the system. Referring now to that point in the receiving and treating circuit where the gas leaves separator 17, a

portion of the gas is diverted through tube 25 to heater 27, the amount diverted being controlled by valve 26. Heater 27 is conventional. It is, of course, desirable, all other conditions being equal, to use as a reactivating gas a gas which has at least been partially dried. It is for that reason that it is preferred to take the reactivating gas from the circuit after the gas has passed through separator 17. Fuel for the heating is delivered thereto from any convenient source (including a point in the system) by pipe 47. The temperature of the heater is regulated to deliver therefrom gas at reconditioning or reactivating temperature. These temperatures are known and depend upon the sorbent used in the drying tower. For instance, when adsorbent alumina is the sorbent used, the temperature of the gas as it leaves the heater should preferably be in the range of 350 to 600 degrees Fahrenheit. On leaving the heater, the diverted and now heated gas passes through tube 28 to a drying tower and thence from the tower through tube 29, then through heat exchanger 30, where the gas is somewhat cooler, then through separator 31 and tube 32, which directs the gas flow into the drying tower then being used in the receiving and treating circuit, at which point the diverted gas rejoins the receiving and treating circuit and becomes a part thereof. The function of heat exchanger 30 will be later described. The function of separator 31 is to separate condensate, which condensate passes through pipe 48 to a suitable place. It will be noted that by manipulation of valves 43 and 44 this sorbent reactivation circuit is diverted through and includes the drying tower which is not, at that moment, a portion of the receiving and treating circuit, while the gas diverted to the sorbent reactivation circuit is finally returned to the receiving and treating circuit through tube 32 and dried in the other drying tower.

The feed circuit which delivers dry gas to the well circuit

This circuit begins at a point in the receiving and treating circuit between the drying tower and expansion motor 22 and terminates when it delivers the dried gas to the well casing for mixture there with the moisture-bearing natural gas being recovered. Thereafter the dried gas is returned to the receiving and treating circuit in said mixture subject, of course, to incidental losses which may occur at the bottom of the well casing. The dried gas enters this circuit through tube 33, the amount so diverted from the principal circuit being controlled by valve 46. The gas then passes through compressor 34, where it is compressed to a pressure desirable or necessary for its subsequent entry into the well. From the compressor 34 the compressed dry gas passes through tube 35 to and through heat exchanger 30 and thence through pipe 14 to the well. In heat exchanger 30 the temperature of the dried gas is raised by the heat loss of the heated gas from the reactivation circuit which, as above described, likewise passes through said exchanger. The heating of the dry gas prior to the time it enters the well is desirable as additional assurance that corrosion condensate will not form on the walls of the well elements. The amount of gas diverted to this circuit will depend, as above described, on the temperature conditions existing in the well and at the surface and the moisture content of the natural gas being recovered.

From the above description of the illustrated, and preferred, form of gas handling system, it will

be apparent that, viewed as a whole, the system includes, in combination, at least two drying towers or means containing sorbent, a gas drying circuit including at least one of said towers and in which natural gas delivered from a gas well is dried at substantially the pressure of delivery, a reactivating circuit receiving undried gas from the drying circuit, including at least one of said towers and also including means for heating the undried gas prior to its entry into said tower, this reactivating circuit terminating in the drying circuit at a point prior to final drying, and a feed circuit adapted to divert a portion of the dried gas from the drying circuit to the well, this feed circuit including means for compressing the gas operable by expansion of the dried gas traveling through the drying circuit and also including heating means for raising the temperature of the compressed gas, said heating being effected by transfer of heat from the gas traveling in the reactivation circuit.

Thus far the above described system has been considered as an improved means for carrying out the previously described corrosion preventing methods of the invention. It will be noted that even in this form the reactivation circuit may be eliminated without destroying the system's usefulness as applied to such methods. For instance, if the drying agent used in the drying tower is of a type which cannot be revived or reactivated after use, or if the reactivation force or fluid is best furnished separately of the system, then the system described may be modified by removing the reactivation circuit or by shutting valves 28, 44 and 45, in which case if heating of the compressed gas in the dry gas feed system is desirable, this heating may be accomplished by separate means or, where the gas issuing through tube 13 is quite warm, by heat exchange with drying circuit.

Likewise the above described system may be used solely as a drying system in cases where no feed of dry gas to the well is desirable or necessary or where dry gas is fed to the well from another source. In this case the feed circuit may be eliminated or, equivalently, valve 46 may be closed. In such case, if cooling of the reactivating gas is desired, the cooling may be effected by other means or by heat exchange with a portion of the dried gas after expansion. Likewise the expansion motor may be eliminated and replaced by a conventional expansion chamber, or the motor may be retained and the expansion energy translated thereby into useful work of any kind.

In a further modification of the system, whether used solely as a drying system or also as a means of furnishing dry gas to the well, the return of the gas in the reactivation circuit to the drying operation may be eliminated. This case presupposes either that mixture of the reactivation gas directly with the dried gas will not unduly raise moisture content of the mixture or that the reactivation gas is of such small quantity that wastage thereof is of no importance. In the first case the valve 45 may be closed and the gas issuing from separator 31 delivered through a by-pass tube 36 to tube 24, or tube 32 may be directly connected to the consumer line and its connections with the drying towers eliminated. In the second case the reactivation gas could be delivered to the atmosphere from separator 31 or delivered and burned at some convenient point.

Another modification of my system now to be explained is particularly adapted to carry out a modified method of corrosion prevention in which

elimination of condensation depends upon the heat of the gas fed into the well rather than the lack of moisture in the gas. In the practice of this modification of my method there is fed into the casing for mixture with the natural gas a gas heated to such temperature that when mixed with the natural gas in the volume desired, the total mixture will be at such temperature that no substantial condensation will occur during passage of the mixture from the earth to the handling system. Thus, in this method the feed gas is preconditioned with respect to temperature rather than with respect to moisture content, the result being the same. The system above described may conveniently be used to achieve this result by bleeding a portion of the undried heated gas from the heater 27 directly to tube 14, as through tube 50, in which case the valves 46 would be closed or the dry feed circuit to the well, apart from tube 14, entirely eliminated.

These and similar modifications will suggest themselves to those skilled in the art, in the practice of my improved methods, as will such details as the fact that the casing may be utilized as the carrier for the up-coming gas in the well, while an auxiliary tube may be used to transmit conditioned incoming gas to the lower regions of the well, and all such modifications are within the purview of this invention, except as limited by the terms of the appended claims.

The advantages of the gas handling systems herein described are manifold. The preferred form described, comprising the three interdependent circuits, efficiently utilizes the energy inherent in the pressure of the gas issuing from the well and likewise cuts heat losses to a minimum, while at the same time conditioning the gas to be fed to the well. Considered as a drying system, and without reference to the conditioning of gas for well use, my system allows the use and reuse of sorbent drying means at a minimum of operating expense. Considered as a two-circuit gas drying system adapted to supply conditioned gas to a well, and without reference to the reactivation circuit, my system offers an economical means for carrying out the preferred phase of my method of preventing corrosion of the well elements without material loss of gas during operation.

Having thus described my invention, I claim:

1. A system for receiving, handling and treating moisture bearing gaseous hydrocarbon fluid issuing, under relatively high pressure, from a well, said system comprising, in combination, a receiving and treating circuit comprising, in recited sequence, means for receiving the gaseous fluid from said well, means for holding a mass of gas drying sorbent in the path of flow of said gaseous fluid, and means for expanding the dried gaseous fluid prior to delivery thereof from the circuit, said circuit being adapted to maintain the gaseous fluid at the approximate pressure of its receipt, subject to changes in temperature and the herein recited diversions of fluid from said circuit, until said gaseous fluid enters said expansion means, a sorbent reactivating circuit including, in recited sequence, means for diverting thereto a portion of the gaseous fluid flowing in said receiving and treating circuit, means for heating the diverted gaseous fluid, means for holding a mass of sorbent in the path of flow of the thus heated gaseous fluid and means for returning said gaseous flow to said receiving and holding circuit, and a feed circuit for feeding dried gaseous fluid from said receiv-

ing and holding circuit into said well, said feed circuit including, in recited sequence, means for diverting thereto a portion of said dried gaseous fluid, means for compressing the diverted dried gas and means for delivering said compressed gas into said well, said compressing means being operable by the expansion means of the said receiving and treating circuit, and a heat exchanging means disposed in said system to transfer a portion of the heat content of the gaseous fluid flowing through said returning means of the said reactivation circuit to the gaseous fluid flowing through said delivery means of the said feed circuit.

2. A system for receiving, handling and treating moisture bearing gaseous hydrocarbon fluid issuing, under relatively high pressure, from a well, said system comprising, in combination, a receiving and treating circuit comprising, in recited sequence, means for receiving the gaseous fluid from said well, means for holding a mass of gas drying sorbent in the path of flow of said gaseous fluid, and means for expanding the dried gaseous fluid prior to delivery thereof from the circuit, said circuit being adapted to maintain the gaseous fluid at the approximate pressure of its receipt, subject to changes in temperature and the herein recited diversions of fluid from said circuit, until said gaseous fluid enters said expansion means, a sorbent reactivating circuit including, in recited sequence, means for diverting thereto a portion of the gaseous fluid flowing in said receiving and treating circuit, means for heating the diverted gaseous fluid, means for holding a mass of sorbent in the path of flow of the thus heated gaseous fluid and means for returning said gaseous flow to said receiving and holding circuit, and a feed circuit for feeding dried gaseous fluid from said receiving and holding circuit into said well, said feed circuit including, in recited sequence, means for diverting thereto a portion of said dried gaseous fluid, means for compressing the diverted dried gas and means for delivering said compressed gas into said well, said compressing means being operable by the expansion means of the said receiving and treating circuit, a heat exchanging means disposed in said system to transfer heat from gaseous fluid flowing through the returning means of said reactivation circuit to gaseous fluid flowing through the delivery means of said feed circuit and another heat exchanging means disposed in said system to transfer heat from gaseous fluid flowing through the receiving means of the receiving and treating circuit to gaseous fluid flowing from the expansion means of the same circuit.

3. A system for receiving, handling and treating moisture bearing gaseous hydrocarbon fluid issuing, under relatively high pressure, from a well, said system comprising, in combination, a receiving and treating circuit comprising, in recited sequence, means for receiving the gaseous fluid from said well, means for holding a mass of gas drying sorbent in the path of flow of said gaseous fluid, and means for expanding the dried gaseous fluid prior to delivery thereof from the circuit, said circuit being adapted to maintain the gaseous fluid at the approximate pressure of its receipt, subject to changes in temperature and the herein recited diversions of fluid from said

5
10

circuit, until said gaseous fluid enters said expansion means, and a feed circuit for feeding dried gaseous fluid from said receiving and holding circuit into said well, said feed circuit including, in recited sequence, means for diverting thereto a portion of said dried gaseous fluid, said means being positioned to divert said portion prior to its entry into the expansion means of the receiving and treating circuit, means for compressing the diverted dried gas and means for delivering said compressed gas into said well, said compressing means being operable by the expansion means of the said receiving and treating circuit.
